UNITED STATES PATENT OFFICE.

JAMES W. ANDERSON, OF SAN FRANCISCO, CALIFORNIA.

SAFETY-RAZOR.

1,200,794.

Specification of Letters Patent.

Patented Oct. 10, 1916.

Application filed September 15, 1915. Serial No. 50,783.

To all whom it may concern:

Be it known that I, JAMES W. ANDERSON, a citizen of the United States, residing in the city and county of San Francisco and State 5 of California, have invented new and useful Improvements in Safety-Razors, of which the following is a specification.

This invention relates to improvements on what is known in the trade as a Durham 10 duplex safety razor.

One of the objects of the present invention, is to provide a two piece guard plate, one section of which forms the guard, while the other section serves as a clamping plate 15 to secure the blade on the razor.

Another object of the invention, is to provide a hinge connection between the two plates together with a locking device for securing same together, which, when released, will permit the guard plate to be folded back on the shank of the razor, in this manner exposing the blade and permitting the four sides of the blade to be honed or stropped without removing the blade.

25 Further objects will hereinafter appear.

The invention consists of the parts and the construction and combination of parts as hereinafter more fully described and claimed, having reference to the accompanying drawings, in which—

Figure 1 is a perspective view of the razor, showing the blade and guard plate removed. Fig. 2 is a view of the blade. Fig. 3 is a perspective view of the sectional guard plate, 35 showing the clamping plate partly opened. Fig. 4 is a cross section, on line 4—4, Fig. 3. Fig. 5 is an enlarged, vertical, longitudinal section through the razor, showing the parts in locked position. Fig. 6 is a plan view, 40 showing the blade applied and guard plate to be turned back to permit the blade to be stropped.

The Durham duplex safety razor, which is extensively used at the present time, is 45 provided with a stropping attachment. In order to use the stropping attachment, it is necessary to remove the guard plate and then apply the stropping attachment; this stropping attachment when applied, only permits 50 the stropping of one edge of a blade, and to permit stropping of the other edge or side of the blade, it is necessary to remove the stropping attachment, reverse the blade and again apply the stropping attachment. This 55 operation takes time, and is more or less inconvenient, as it necessitates removal and

reversal of the blade several times, before both edges are stropped.

The object of the present invention, is to provide a sectional guard plate, one section 60 of which can be folded back on the shank of the razor, in such a manner that both cutting edges of the blade are uncovered, or so exposed that both cutting edges may be stropped without removing or reversing the 65 blade. This is accomplished in the following manner:

Referring to Fig. 1, A indicates a handle; 2 the shank pivotally mounted therein, and 3 the holder upon which the blade 4 is supported and clamped by the guard plate, generally indicated in Fig. 3. This guard plate is in the present instance, made in two sections, 5 and 6; said sections being secured together by a hinge connection 7. The plate 70 5 is provided with a pair of downwardly turned, flexible spring tongues 8 (similar in construction to those now in use), which are adapted to pass through the slot 9, in the blade and the openings 10, in the holder, to 75 secure the blade in the usual manner, while the other plate 6, is provided with the outwardly extending guard fingers 11.

Slidably mounted in a slot 12, formed on the guard plate 6, is a locking device consisting of a plate 13, in the forward end of which is formed a hook-shaped latch 14, which projects through slot 12 sufficiently far to engage the clamping plate 5, as shown 80 in Fig. 5.

In operation when it is desired to place a blade in position on the holder 3, it is first necessary to lay the blade on the clamping plate 5, in a position where the spring tongues 8 will project through slot 9 in the 85 blade. The blade together with the clamping plate and guard plate 6, is then placed upon the holder 3, in a position where tongues 8 will project through the openings 10. The connected plates 5 and 6 together with the shaving blade is then moved in the direction of the shank 2 or handle A, causing the spring tongues to enter a pair of shallow pockets 10^a formed adjacent to the 90 openings 10.

If it is desired to strop the blade when applied to the holder, as described it is only necessary to move the plate 13 with the lock in the direction of arrow a; this causes the latch 14 to move out of engagement with 95 the clamping plate into the dotted line position, shown in Fig. 5. The guard plate is 100 105 110

then free to move about the hinge 7, in the direction of arrow b, and may be folded down flat with relation to the shank 2 and handle A. This position is shown in Fig. 6. 5 By referring to this figure, it will be seen that both the cutting edges of the blade 4 are exposed. The razor may then be stropped like an ordinary razor, first to sharpen one cutting edge, and then the opposite cutting 10 edge; this being accomplished without removing the blade from the razor. After the blade has been sharpened on both edges, and it is desired to shave, it is only necessary to swing the guard plate about hinge 7, till it 15 lies flat upon the clamping plate 5, it is then secured by sliding the plate 13 back into the full line position, shown in Fig. 5, where the latch engages with the clamping plate. The razor is then ready for use, and both 20 cutting edges are guarded by the fingers 11, which project over the edge of the blade.

For the purpose of making the sectional guard plate as compact and flat as possible and also for the purpose of bringing the 25 guard fingers 11 into the correct position with relation to the cutting edges of the blade, it is preferable to form a channel 16, on the lower side of plate 6, which is sufficiently deep to receive the clamping plate 5. This 30 produces a compact, flat construction and adds very little to the weight or cost of construction.

The razor as a whole, is substantially the same as the Durham duplex safety razor on 35 the market, the only change in construction being that of the guard plate, which in this instance, is made in two sections. The openings produced in the clamping plate by forming the tongues 8, together with the 40 slot 9, formed in the blade permits the application of the locking device without making any changes or alterations in construction of the parts already manufactured.

As the latch 14 on the locking device is so 45 positioned, that is passes through slot 12 and the opening 8^a in the clamping plate directly into the slot 9 of the blade, the sectional guard plate may therefore, be bought as an attachment to the razors now manufactured 50 or in use, and applied directly to same without making any changes or alterations. The sectional guard plate constructed as here shown protects the razor blade in the usual manner, and may be folded back away from 55 the blade without any trouble or loss to time, thus permitting both cutting edges of the blade to be honed or stropped without removal or the application of any other device.

The majority of safety razors including 60 the Durham duplex safety razor, now in use have extra stropping attachments, which cause considerable delay when shaving, as it is necessary to remove the old guard plate and turn the blade about while stropping the 65 two cutting edges. The hinge on the guard

plate proper furthermore permits cleaning of the blade, etc., the lather or any other accumulation may be removed, by simply opening the guard plate.

It is particularly to be noted that the 70 blade 4 is, when the guard is swung back to rest against the shank 2, located between the holder 3 and the section 5 of the guard plate and is clamped rigidly by the section 5 alone, and independent of section 6. This clamping of the blade by section 5 alone is of vital importance since in order to strop, the guard section 6 must be moved to inoperative position in which it is incapable of holding the blade rigid. Further the opposite longitudinal sides of the holder 3 and the section 5 serve to provide guides which hold the blade at the proper angle to the strop during stropping. The hinge 7 of the guard section 6, is also located at the inner end of the blade 85 so that the same may be swung to lie between the inner end of the blade and the handle A and be held immovable by the thumb of the operator and in a position to not interfere in any manner with stropping 90 of the blade.

The tongues 8 are struck-out leaving apertures, and the slideable latch 14 operates in the aperture formed by the striking-out of one of the tongues as depicted in Fig. 5 so as to engage the inner face of the section 5. 95

The materials and finish of the several parts of the device may be such as the judgment and experience of the manufacturer may dictate. 100

I wish it understood that various changes in form, proportions and minor details of construction may be resorted to within the scope of the appended claims, and that I do not wish to limit myself to the specific 105 design and construction here shown.

Having thus described my invention, what I claim and desire to secure by Letters Patent is—

1. In combination with a razor handle 110 having an apertured shank, a guard composed of an inner blade clamping section having struck-out tongues engageable in the shank apertures, and an outer section having a latch engageable in one of the openings formed by the struck-out tongues of the inner section. 115

2. In combination with a razor handle having an apertured shank, a guard composed of an inner blade clamping section having struck-out tongues engageable in the shank apertures, and an outer section hinged at its inner end to the inner end of the inner section and having a latch engageable in one of the openings formed by the struck-out 125 tongues of the inner section.

3. A safety razor comprising a blade, a blade holder, a detachable clamp for securing the blade to the holder, said clamp having an opening therein, a guard hinged to 130

the clamp, and a locking device on the guard having a hook part adapted for engagement in the clamp opening to secure the guard and clamp together.

- 5 4. A safety razor comprising a blade holder having spaced openings, a blade having an elongated opening, a blade clamp having tongues passing through the blade opening and engaging in the holder openings, said clamp further having an opening over the blade opening, a guard, and a locking device carried by the guard and provided with a hook part adapted for engaging in the clamping opening, the blade serving as a spacer between the clamp and holder to permit of the hook terminal engaging the inner face of the clamp.
- 10 5. In combination with a handle having

a rigid blade holder disposed in substantially the same plane therewith, a clamp removable from the holder for clamping a double-edged blade to the holder, a guard movably connected to the clamp so as to be removable from the holder with said clamp, and a latch for securing the guard positively 25 to said clamp, said guard being movable to an inoperative position while the clamp is in clamping position to expose both edges of a blade for stropping.

In testimony whereof I have hereunto set 30 my hand in the presence of two subscribing witnesses.
